(57) **CLAIM**

The ornamental design for a serration part for a rotor blade of a wind turbine as shown and described.

DESCRIPTION

1. Serration part for a rotor blade of a wind turbine
2. Serration part for a rotor blade of a wind turbine
- 1.1 is a perspective view of a first embodiment of a serration part for a rotor blade of a wind turbine;
- 1.2 is a top view thereof;
- 1.3 is a side view thereof;
- 1.4 is a front view thereof;
- 1.5 is a perspective view thereof showing the serration part for a rotor blade of a wind turbine attached to a rotor blade of a wind turbine;
- 1.6 is a side view thereof;
- 1.7 is a bottom view thereof;
- 2.1 is a perspective view of a second embodiment of a serration part for a rotor blade of a wind turbine;
- 2.2 is a top view thereof;
- 2.3 is a side view thereof;
- 2.4 is a front view thereof; and
- 2.5 is a top view thereof showing the serration part for a rotor blade of a wind turbine attached to a rotor blade of a wind turbine.

The broken lines in the drawings illustrate environmental features and portions of the serration part for a rotor blade of a wind turbine that form no part of the claimed design.
